UNITED STATES PATENT OFFICE.

ROBERT N. McDONOUGH AND JAMES M. CONWAY, OF FOSSIL, ALABAMA.

GAS-GENERATOR.

No. 926,889.

Specification of Letters Patent.

Patented July 6, 1909.

Application filed October 31, 1908. Serial No. 460,689.

To all whom it may concern:

Be it known that we, ROBERT N. McDONOUGH and JAMES M. CONWAY, citizens of the United States, residing at Fossil, in the county of Jefferson and State of Alabama, have invented new and useful Improvements in Gas-Generators, of which the following is a specification.

Our invention relates to an improvement in an apparatus for the manufacture of gas from coal, wood, or other combustibles, which consists in the novel construction and combination of parts hereinafter more particularly described and claimed, reference being had to the accompanying drawings, in which:

Figure 1 represents a longitudinal sectional view through a boiler furnace equipped with our improved gas generating apparatus. Fig. 2 is a vertical transverse sectional view taken along the line $z-z$ of Fig. 1.

Similar reference numerals refer to similar parts throughout the drawings.

We have illustrated our invention in its preferred form for use in connection with the ordinary type of boiler furnace, and more particularly such furnaces as are provided with Dutch ovens or fire boxes set in front of the boiler.

The casing 1 of the boiler furnace, which may be of any standard construction, has mounted in the forward end thereof, over the fire-box 2, a transversely disposed cylindrical drum 3, the heads of which preferably project beyond the side walls of the casing and the bottom of which stands sufficiently high above the grate bars 4 to permit the natural flow of gases over the bridge wall 5 and around the baffle 6, during which passage they operate with the usual effect upon the tubular boiler 7, and, after passing over the top of the drum 3, they flow off through the stack 8. We feed the material, from which the gases are to be distilled, into the drum at one end through a chute or feed tube 9, which extends up through the top wall of the casing and connects above with a hopper 10. Between the hopper and the top of the casing the feed tube is enlarged at 11 to provide a substantially air tight circular seat for a semi-rotary valve 12 which is pivoted on an axis 13 and operated by a crank 14. This valve is hollow and provided with an open port 15 into which the material drops from the hopper 10 and through which it falls down into the drum 3.

when the valve has been given a semi-rotation. The material, as thus charged into the drum, falls near the left hand end thereof, as seen in Fig. 2. To facilitate the distillation of gases from the material, we provide means to continually stir the same while in the drum which, in the preferred form, comprise a shaft 16 suitably mounted in bearings in the opposite heads of the drum 3 and adapted to be turned by a crank 17. Rigidly connected to this shaft by arms 18 is a stirrer blade 19 which is twisted to give it a tendency to feed the material toward the discharge chute 20 which extends downwardly to any suitable point for the discharge of the coke and ashes from the drum. This chute 20 is provided with a valve 21 similar to 12 and operated by a crank 22 so that in this manner, by the use of the valves 12 and 21, the material can be continually charged and discharged from the casing without the admission of air.

In cases where it is desired to charge material into the drum of such character that it cannot be handled by the valve 12, we provide an auxiliary feeding apparatus comprising a cylindrical casing 23 connected to one of the heads of the drum opposite an opening 24 therein of equal dimensions with the casing 23. The outer end of this casing 23 is closed by a screw cap 25 through which passes the operating rod 26 of a plunger 27, which may be used both for the purpose of forcing material into the drum 3 and also as a means to clean out the same when desired. We provide a valve casing 28 which serves as a guide for a tapered slide valve 29, the bottom end of which fits snugly in the casing 28, and which, when raised by means of the crank arm 30 and stem 31, will valve off the outer end of the casing 23 so that the head 25 can be removed and the material to be charged introduced therein; and after the head 25 has been replaced, the valve can be lowered and the material in the casing forced into the drum 3 by means of the plunger 27 which was withdrawn when the head 25 was removed.

In operation, the material is continually charged and discharged through the chutes 9 and 20 and its gasification facilitated by the operation of the stirrer blade 19. The gases which are generated are carried off by a pipe 32 to a reservoir as 33, and thence to points of use.

Our invention, without materially inter-

fering with the normal operation of the boilers can be operated to produce sufficient gas so that the boiler itself may be fired by the same. To this end we provide a pipe 33' 5 leading from the reservoir to a burner 34 beneath the drum 3 in the fire-box. This arrangement is illustrated in Fig. 2 and under many circumstances will represent a preferred construction.

While we claim particular advantages from the combination of our improved gas generating apparatus with a boiler furnace, yet it may be independently used with advantage in any type of furnace.

Having thus described our invention, what we claim as new and desire to secure by Letters Patent, is:-

1. The combination with a casing, of a gas apparatus comprising a drum transversely disposed within the casing above the fire-box therein, a feed chute for said drum which projects without said casing near one end thereof, an auxiliary feeding apparatus comprising an extension casing, having a detachable outer head and an intermediate valve, which connects with said drum at another

point, a valve controlled discharge chute leading from said drum, and means, operable from without the furnace, which both feed and stir the material in the drum, substantially as and for the purposes described.

2. A gas generating apparatus comprising a drum, a furnace to heat said drum, valve controlled feed and discharge chutes at opposite ends of said drum, an auxiliary feed 35 means disposed near the discharge chute and comprising a casing opening into the drum, a valve disposed at an intermediate point in the casing, a detachable head for the outer end of said casing, and a plunger which 40 passes through said casing and is adapted to enter said drum, as and for the purposes described.

In testimony whereof we have hereunto set our hands in presence of two subscribing 45 witnesses.

ROBERT N. McDONOUGH.
JAMES M. CONWAY.
